UNITED STATES PATENT OFFICE.

HARRY B. McBEE, OF ST. LOUIS, MISSOURI, ASSIGNOR TO McBEE BINDER COMPANY, OF ATHENS, OHIO.

MOUNTING FOR MAKE-UP FRAMES FOR PRINTING PRESSES.

Application filed September 26, 1921. Serial No. 502,316.

To all whom it may concern:

Be it known that I, HARRY B. McBEE, a citizen of the United States, residing at St. Louis, Missouri, have invented a new and useful Improvement in Mountings for Make-Up Frames for Printing Presses, of which the following is a specification.

My invention relates to the printing art and has for its purpose to produce efficient and satisfactory means for forcing a make-up frame against any article designed to receive an impression, regardless of whether, or not, the article is lying in a true and exact horizontal plane, or whether or not the article is of uniform thickness.

A further object is to so construct the co-acting parts that the make-up frame will first contact one side of the article to be impressed, and will then have a relatively rotary motion in seating itself firmly against the article.

A yet further object is to construct the frame so that it may be turned upwardly, with a rotary motion on its bearings, and be held in position, face up, while the type is being placed therein.

In the drawings I have illustrated the various parts of my device, reference to which is made in the appended specification and set forth in the claims.

Figure I of the drawing shows a portion of the make-up carrying shaft, together with the make-up frame thereon, in perspective;

Figure II shows a side elevation view of the same, the dotted lines indicating the position of the make-up frame ready to be rotated upwardly to receive the make-up;

Figure III shows a side elevation view of my device, the shaft being in section; and Figure IV shows a side elevation view of my make-up frame, rotated upwardly to receive the make-up, the dotted lines indicating the normal position of the frame.

Referring to the accompanying drawings, the reference numeral 10 is used to indicate the carrying shaft of the make-up frame, and the numeral 11 indicates the make-up frame depending therefrom and rotatably and slidably, mounted thereon.

The numeral 12 indicates a bearing secured to the shaft 10 and provided with arms 13 and 14, extending inwardly therefrom to a position over the make-up frame 11, one on each side of the shaft 10, said arms being designed to receive, for rotation

and adjustment therein, the screw-threaded adjustment shafts 15 and 16, which depend downwardly therefrom to positions over their respective sides of the make-up frame 11. The make-up frame 11 is, as stated, 60 designed for slidable movement on the shaft 10, and the screw-threaded shafts 15 and 16 are positioned so as not to interfere with this slidable movement, which is designed to be such as to move the frame 11 until it is out of the plane of the shafts 15 and 16, at which time the make-up frame may be rotated at will, on the shaft 10. On the shaft 10 I have provided a lug 17, which limits the movement of the make-up frame, and a 65 companion lug 18 on the side of the make-up frame is designed to engage the lug 17, the construction and positioning of these lugs being such that when the make-up frame is rotated on the shaft 10, until the 70 lugs 17 and 18 engage, the make-up frame will be rotated slightly more than one-half of a revolution, the face of the make-up frame being turned upwardly to receive the make-up, and as the rotation has been slightly more than one-half, the lugs 17 and 18 will operate, with the weight of the 75 make-up frame, to hold it in this position.

In practical operation the shaft 10 is designed to move downwardly or upwardly, 80 as selected by the operator. In desiring to change the make-up, the shaft 10 is moved upwardly, the make-up frame 11 moved by a sliding movement, on the shaft 10 until it is beyond the screw-threaded shafts 15 and 16, and rotated until the lug 18 engages the lug 17. The operator then inserts the make-up in the make-up frame. The frame is then rotated downwardly and moved on the shaft until it is in proper position, underlying the ends of the screw-threaded shafts 15 and 16. These shafts are then 85 adjusted as desired by the operator, to cause the make-up frame to assume any angle desired for meeting the face of the work. By 100 this construction the surface of the work does not necessarily have to be in a perfectly true horizontal plane, but may even be on quite an angle and the pressure will be applied to the make-up frame equally, 105 nevertheless.

A very important feature of my invention is the fact that the rotary mounting of the make-up frame on the shaft 10 will cause pressure on the shaft 10 to equalize itself on 110

the make-up frame pressing against the work. This is obvious because of the fact that if one edge of the make-up frame contacts the work first, the continued downward pressure of the shaft 10 forces the make-up frame to equalize itself on the work by a slight rotation on the shaft 10, thus completely equalizing the pressure that is continued to be applied. In practice this has proven to be of great service because it has practically eliminated the occasional mackle which so often occurs in printing. Furthermore, my rotatably mounted make-up frame provides for satisfactorily making impressions on work which may be resting at more or less of an angle from the true horizontal, or when the article is not of uniform thickness. In addition to these features, it also functions to produce a very satisfactory imprint upon work which may have more or less resiliency, such as the back of a book which has been opened and placed in spread position on the bed plate.

Having thus described my invention, what I claim and desire to secure by Letters Patent of the United States, is:

1. In a printing press, a make-up frame mounted for limited rotary movement on a carrying shaft: means on the carrying shaft for limiting the rotation of the make-up frame, said means being such as to also function for retaining the make-up frame in its rotated position, substantially as shown and described.

2. In a printing press, a make-up frame rotatably mounted on a carrying shaft; a

bearing secured to said shaft, and screw threaded adjustment shafts rotatably mounted in screw threaded orifices therein, one on each side of the carrying shaft, substantially as shown and described.

3. In a printing press, a make-up frame rotatably and slidably, mounted on a carrying shaft; a bearing secured to said shaft, and screw threaded adjustment shafts rotatably mounted in screw threaded orifices therein, one on each side of the carrying shaft; a lug on the carrying shaft to limit the slidable movement of the make-up frame, substantially as shown and described.

4. In a printing press, a make-up frame rotatably and slidably, mounted on a carrying shaft; a bearing secured to said shaft, and screw threaded adjustment shafts rotatably mounted in screw threaded orifices therein, one on each side of the carrying shaft; a lug on the carrying shaft to limit the slidable movement of the make-up frame; a lug on the make-up frame to engage the lug on the shaft when the make-up frame has been rotated upwardly on the said shaft, the positioning of the lugs on the make-up frame and the shaft being such that when they engage each other the make-up frame will be held in position with its face upward to receive the make-up, substantially as shown and described.

HARRY B. MCBEE.
